(57) **CLAIM**

The ornamental design for a holder for a spray bottle with sponge, as shown and described.

DESCRIPTION

FIG. 1 is a left side perspective view taken from the front and above showing our new design;

FIG. 2 is a left side elevational view thereof;

FIG. 3 is a right side elevational view thereof;

FIG. 4 is a plan view thereof;

FIG. 5 is a bottom view thereof;

FIG. 6 is a front view thereof; and,

FIG. 7 is a rear view thereof.

The broken line showing a spray bottle with sponge is for illustrative purposes only and forms no part of the claimed design.
